United States Patent Office

Des. 211,601

Patented July 2, 1968

211,601

CLOTHES WASHING MACHINE

Eric John Marshall, Sunnydale, Farnborough Park, England, and Robert H. Hose, Mountainside, N.J., assignors to The Hoover Company, North Canton, Ohio, a corporation of Delaware

Filed Dec. 22, 1966, Ser. No. 5,148

Claims priority, application Great Britain July 13, 1966

Term of patent 14 years

(Cl. D49—1)

Fig. 2

Fig. 1

FIG. 1 is a perspective view of a clothes washing machine, showing the front and one side thereof, embodying our new design;

FIG. 2 is a front elevational view thereof;

FIG. 3 is a side elevational view thereof, the opposite side having substantially the same appearance; and

FIG. 4 is a top plan view thereof.

The dominant features of our design reside in the portions shown in full lines on the drawings.

We claim:

The ornamental design for a clothes washing machine, substantially as shown and described.
